UNITED STATES PATENT OFFICE.

LAUDIE J. MRUK, OF BUTTE, MONTANA.

LUBRICATOR.

1,308,604:

Specification of Letters Patent.

Patented July 1, 1919.

Application filed September 3, 1918. Serial No. 252,365.

To all whom it may concern:

Be it known that I, LAUDIE J. MRUK, a citizen of the United States, residing at Butte, in the county of Silverbow and State 5 of Montana, have invented certain new and useful Improvements in Lubricators, of which the following is a specification.

This invention relates to lubricators specially adapted for use in connection with the 10 cars used in mines and other similar places; and it consists in the novel construction and combination of the parts hereinafter fully described and claimed. A lubricator of this sort is preferably made to hold a considerable 15 supply of hot tallow and of lubricating oil which are kept separate from each other and which are used on different parts of the same car; but it may also be filled with one kind of oil; or it may be filled with 20 any two lubricants of different density or fluidity. In lubricating mine cars it is desirable to have both sorts of lubricant on hand, and in chambers which are connected together in a single device or structure, 25 and to have a liberal supply of each lubricant, so that a number of cars can be lubricated without having to refill the lubricator.

In the drawings, Figure 1 is a vertical section through a lubricator constructed according 30 to this invention. Fig. 2 is a cross-section, taken on the line $x-x$ in Fig. 1.

The shell 2 of the lubricator is preferably a cylinder formed of sheet metal or other suitable material, and it is provided with a 35 bottom 3 at its lower end. A removable cover 4 is secured to the top end of the cylinder. The cylinder has three partition plates or false-bottoms 5, 6, and 7. The upper partition 5 forms the bottom of the 40 grease chamber 8, which is in the upper part of the shell. The middle partition 6 forms the top of the oil chamber 9; and a heating chamber 10 is formed between the two chambers 8 and 9. The partition 7 forms the bottom of the oil chamber 9, and 45 another heating chamber 12 is formed between the partition 7 and the bottom 3.

The bottom of the heating chamber 10 is provided with candle sockets 14, and the 50 bottom of the heating chamber 12 is provided with candle sockets 15. Candles 16 are placed in the candle sockets, and are provided to heat the lubricant in the chambers above them. Four candles are preferably 55 arranged in each heating chamber, but other similar heating devices may be used,

and they may be supported in any approved way. Door openings 18 and 19 are provided in the respective heating chambers 10 and 12, and are formed in the side wall of the 60 shell. These openings are provided with sliding doors 20 and 21 which work in guides 22 and 23 on the shell. Any other approved form of door may be used which will permit the candles being placed in position, and the door may be left slightly open to support combustion, or any suitable air holes may be provided. Each heating chamber may also have a plurality of sliding doors and door openings if desired. 70

A stay 25 is arranged centrally in the lubricator shell, and is secured to the bottom 3 and to the three partitions 5, 6, and 7. This stay strengthens the partitions, and also compensates the shell for the loss of 75 material cut away to form the door openings of the heating chambers. The partitions 5, 6, and 7, are also reinforced, thickened or braced in any approved way where the stay is secured to them. The lower 80 part 26 of the stay may be a solid rod of metal, and its upper part 29 is preferably tubular and is provided with a T junction pipe 27 having an oil outlet 28 on one side which discharges into the oil chamber 9. 85 The tubular upper part 29 of the stay extends through the upper heating chamber. A plug 30 is provided for closing the upper end of the tube or pipe 29. When this plug is removed it may be screwed into a 90 socket 31 on the top partition plate to hold it stationary and prevent its loss.

The oil chamber 9 is provided with an oil inlet or charging hole 32 having a suitable cap, and it has an oil outlet branch or pipe 95 33 to which any suitable flexible oil pipe and regulating valve are attached. A check valve 34 is also provided, and compressed air is forced into the upper part of this chamber 9 from time to time so as to expel 100 the oil.

The upper chamber 8 is filled with tallow or other normally stiff grease by removing the cover, or in any other convenient way. The upper chamber is also provided with an 105 outlet branch or pipe 35 for the connection of a flexible pipe or other attachments, and it has a check valve 36 to admit compressed air to expel its contents when it is used for oil. 110

The thick grease is preferably expelled from the chamber 8 by means of a piston 38

which is slideable in the chamber. A screw-threaded push-rod 40 engages with a screw-threaded hole in the center of the piston, and this rod is journaled in a bearing 41 on the cover, and is provided with a handle 42. Collars 43 are provided on the rod to prevent it from sliding longitudinally in the bearing. The piston is operated by revolving the push-rod. The piston is prevented from revolving by its frictional contact with the wall of the chamber, but any suitable guide may be provided if desirable.

When stiff grease is not required, and a large supply of oil is desirable, the plug 30 is removed, and oil is poured into the upper chamber until both chambers are filled. The candles of the two heating chambers heat the oil, and prevent it from freezing when the temperature is very low.

20 When a lubricator of this construction is used, a large number of cars can be lubricated without having to refill the device. As each car is lubricated by the one device there is less danger of parts of a car being overlooked, or of cars being overlooked altogether, which is apt to be the case when small separate lubricators are used for grease and for oil. By having a single shell provided with chambers for grease and oil arranged one above the other, and having two heating chambers, the shell can be made of relatively small diameter, which is desirable when used around mine cars, and a liberal supply of lubricant can be carried about 30 from car to car and kept in condition for use.

What I claim is:

1. In a lubricator, two superposed chambers for lubricant, a chamber for heating devices interposed between the said chambers, 40 and a pipe connection between the two chambers for lubricant extending through the heating chamber.

2. A lubricator formed of a single shell provided with partitions dividing it into separate chambers for lubricating material and heating chambers, said chambers being arranged one above another, and the chambers for lubricant being provided with a pipe connection which extends through the heating chamber intervening between them. 50

3. A lubricator formed of a single shell provided with partitions dividing it into separate chambers for lubricating material and heating chambers, said chambers being arranged one above another, and the chambers for lubricant being provided with a pipe connection which extends through the heating chamber intervening between them, means for closing the said pipe connection at will, and separate means for controlling 60 the outlet of lubricant from its chambers. 55

4. In a lubricator, a shell provided with partitions which divide it into superposed chambers for lubricating material and for heating devices, said chambers being arranged alternately, and means for bracing together the central portions of the said partitions. 65

5. A lubricator formed of a single shell provided with partitions dividing it into separate chambers for lubricating material and heating chambers arranged one above another, said heating chambers having openings formed in the wall of the shell, and a brace secured between the said partitions and extending through the said heating chambers and the chamber for lubricant extending between them, said brace having a tubular portion which forms a pipe connection between the upper and lower chambers for lubricant. 70 75 80

In testimony whereof I have affixed my signature.

LAUDIE J. MRUK.
